CLAIM

The ornamental design for a ratcheting pipe wrench, as shown and described.

DESCRIPTION

FIG. 1 is a side elevational view of a ratcheting pipe wrench showing my new design;

FIG. 2 is a top, front perspective view thereof;

FIG. 3 is an opposite side elevational view thereof.

FIG. 4 is a rear elevational view thereof;

FIG. 5 is a bottom plan view thereof.

The broken line showing of a pipe in FIG. 1 is for illustrative purposes only and forms no part of the claimed design.

FIG. 1.

FIG. 2.

FIG. 3.

FIG. 4.

FIG. 5.
